UNITED STATES PATENT OFFICE.

GEORGE A. ROSENFELDER, OF PITTSBURGH, PENNSYLVANIA.

CRYSTAL DETECTOR.

Application filed, March 3, 1924. Serial No. 696,608.

To all whom it may concern:

Be it known that I, GEORGE A. ROSENFELDER, a citizen of the United States, residing at Pittsburgh, in the county of Allegheny and State of Pennsylvania, have invented new and useful Improvements in Crystal Detectors, of which the following is a specification.

This invention relates to detectors, and 10 more particularly to a crystal detector for use in radio receiving sets.

One of the main objects of the invention is to provide a device of this character in which the filament or "cat's-whisker," or 15 corresponding element will be held in adjustment after it has been placed upon a sensitive spot in the crystal of the detector. A further object is to provide simple and efficient means for holding the "cat's-whisker" 20 in adjustment while permitting it to be adjusted when desired. Another object is to provide means whereby the pressure on the "cat's-whisker" may be regulated for obtaining the best results. Further objects will 25 appear from the detail description.

In the drawings:—

Fig. 1 is a front view of the device as applied;

Fig. 2 is a central vertical section through 30 the device, on an enlarged scale, parts being shown in elevation;

Fig. 3 is a section taken substantially on line 3—3 of Fig. 1;

Fig. 4 is a section taken substantially on 35 line 4—4 of Fig. 2.

The device includes a barrel 1 formed of any suitable or preferred electrical insulating material. A collar 2 is secured on the upper end of barrel 1 and is bored and threaded for reception of a screw plug 3 provided, at its upper end, with outwardly projecting arms 4 which are secured in any suitable or preferred manner to a disc 5 of electrical insulating material. A cup member 6 is threaded on the lower end of barrel 1, this member being adapted for reception of a mounting 7 for a crystal 8 of galena, or any other suitable or preferred material such as is used for this purpose in crystal receiving sets.

A brass rod 9 is slidably and rotatably mounted through disc 5 and plug 3 which are suitably bored for this purpose. This rod extends through barrel 1 to within a short distance of the lower end thereof, and the lower end of the rod is tapered to pro-

vide a frusto-conical element 10 which extends through a downwardly tapering opening provided through an annulus 11 seated on a shoulder 12 formed within barrel 1 by 60 reducing the lower portion 13^a of bore 13 of the barrel. An expansion coil spring 14 is mounted about rod 9 and is confined between plug 3 and a collar 15 secured upon the rod substantially centrally thereof. A 65 second coil spring 16 is mounted about the lower portion of rod 9 and is confined between collar 15 and annulus 11. This provides a spring mounting for the rod which permits it to be adjusted in either direction 70 by turning plug 3 in collar 2 and the springs and associated parts act to hold the rod in adjustment. As its lower end rod 9 is provided with an angularly disposed contact member 17 which may be formed integrally 75 with rod 9 or may be formed as a separate element and secured to the rod. The member 17 is preferably very fine or thin and is adapted to contact with crystal 8, this member forming a contact element which 80 corresponds to the "cat's-whisker" commonly employed in crystal detectors. At its upper end rod 9 is provided with a knob 18 secured thereon, this knob being formed of any suitable or preferred electrical insulat- 85

The detector constructed in the manner illustrated and described is well adapted for use in connection with spring contacts C such as are commonly employed in connection with switch boards, these contacts being positioned and adapted to engage about collar 2 and cup member 6 when the device is in place, it being understood that the contacts or clips C are secured upon a panel P 90 of a radio receiving set and are properly connected into the circuit of the set by means of wires d and d'. As the collar 2, plug 3, spring 14 and rod 9 are all formed of brass or other suitable electrical conducting material, and the cup member 6 is also formed of brass, the electrical impulses or current can flow from wire d to member 17, crystal 8, crystal mounting 7, cup member 6 and the lower clip C to wire d', or vice versa, 95 as will be understood. When the device is applied, by turning rod 9 by means of knob 8, the contact element 17 may be moved over the surface of crystal 8 until this member is positioned upon a sensitive spot in the 100 crystal. After this has been done, the pressure on member 17 may be adjusted by 105

means of plug 3 so as to obtain maximum reception. After the device has been adjusted in the manner described, rod 9 is held in adjustment by the springs and plug and 5 associated parts thus insuring that contact member 17 will not be jarred off of or out of contact with the sensitive spot of the crystal on which it has been placed.

As is known, crystals used in crystal detectors for radio receivers have spots which 10 are more sensitive than other portions of the crystal and it not infrequently happens that considerable trouble is experienced with the type of a detector now in use in placing 15 the "cat's-whisker" on a sensitive spot and keeping it there after this spot has been found. By means of my device, the "cat's-whisker" or contact member 17 can be placed upon a sensitive spot of the crystal 20 and, which is of great importance, is effectually held against casual displacement. This provides a very simple and inexpensive, as well as highly efficient detector which may be readily applied and used in connection 25 with radio receiving sets of standard construction.

What I claim is:—

1. In a device of the character described, a 30 barrel of electrical insulating material, a rod of electrical conducting material extending through the barrel, a crystal supported at one end of the barrel, said rod being provided with a member disposed to contact with the crystal, resilient means for forcing the rod in one direction, resilient means for forcing the rod in the other direction, and positively acting means for exerting pressure on the resilient means for forcing the rod in said other direction.
2. In a device of the character described, a 40 barrel of electrical insulating material, means for supporting a crystal at one end of the barrel, a rod of electrical conducting material extending through the barrel and 45 provided with a contact element disposed to contact with a crystal supported by said crystal supporting means, resilient means for forcing the rod in one direction, resilient means for forcing the rod in the other direc-

tion, and means for increasing and diminishing the force acting to move the rod in one direction for adjusting said rod toward or away from the crystal supporting means. 50

3. In a detector of the character described, a barrel of electrical insulating material, 55 means at one end of the barrel for supporting a crystal, a collar of electrical conducting material secured on the other end of the barrel, a plug of electrical conducting material threaded into the collar, an annulus 60 mounted in the barrel remote from the collar and held against movement in a direction away from said collar, a rod of electrical conducting material extending into the barrel and through said plug, said rod being provided within the barrel with an annular collar, an expansion spring mounted about the rod and confined between said plug and the collar of the rod, and an expansion 65 spring mounted about the rod and confined between the collar of the rod and said annulus, the rod being provided with a contact member disposed to contact with a crystal 70 mounted in said crystal supporting means. 75

4. In a device of the character described, a barrel of electrical insulating material, a cup member of electrical conducting material removably secured on one end of the barrel, an annulus mounted in the barrel beyond the cup member and held against movement toward the same, a collar of electrical conducting material secured on the other end of the barrel, a plug of electrical conducting material threaded into said collar, a rod of electrical conducting material 80 extending through said plug and into the barrel, said rod being provided within the barrel with an annular collar, an expansion spring mounted about the rod and confined between the collar thereof and said plug, 85 and an expansion spring mounted about the rod and confined between said annulus and the collar of said rod, the rod being provided at its inner end with an angularly disposed contact element. 90 95

In testimony whereof I affix my signature.

GEORGE A. ROSENFELDER.
